UNITED STATES PATENT OFFICE.

FRANK D. WINKLEY, OF MADISON, WISCONSIN.

OIL-HOLE COVER OR CAP.

SPECIFICATION forming part of Letters Patent No. 608,243, dated August 2, 1898.

Application filed September 13, 1897. Serial No. 651,506. (No model.)

To all whom it may concern:

Be it known that I, FRANK D. WINKLEY, a citizen of the United States, residing at Madison, in the county of Dane and State of Wisconsin, have invented certain new and useful Improvements in Oil-Hole Covers or Caps, of which the following is a specification.

My invention pertains to improvements in oil-hole covers or caps, the construction and advantages of which will be hereinafter fully set forth, reference being had to the annexed drawings, wherein—

Figure 1 is a perspective view of my improved cap in its closed position; Fig. 2, a similar view, the cap being shown open; Figs. 3 and 4, top plan views of Figs. 1 and 2, respectively; Fig. 5, a longitudinal sectional view of the cap in its closed position; Fig. 6, a similar view, the cap being open; and Fig. 7, a sectional perspective view.

The object of my invention is to provide a simple and efficient cap or cover which may be readily applied to oil-holes of machinery and at the same time one which will be easy of manipulation and thoroughly dust-proof.

Referring to the drawings, A designates a hollow stem or post formed with a cylindrical recess B, extending from the lower end thereof up to the upper end or top C. Said top is provided with an opening D at one side of the center, which communicates with the internal bore B. A cylindrical stud E extends upwardly from the top, as seen in Figs. 5, 6, and 7, and is preferably formed therein at a point diametrically opposite opening D.

An annular groove or recess F is formed around the stem immediately below the top, and openings G are provided in the stem in the upper part of the recess, as shown. These openings are designed to receive a spring H, formed of a single piece of spring-wire, the ends being bent around a slight distance from the stem and downwardly, as indicated in Fig. 7.

The lower part of the stem is reduced, as at I, and also provided with a threaded section J and polygonal section K, the device being designed to be either driven or screwed into place.

L indicates the cover, formed with an opening M of a diameter slightly greater than that of stud E, so that the stud may enter the

same when the parts are in their closed position.

An annular groove N is formed in the inner face of the depending skirt of cover L, the arms of spring H entering said groove when the parts are assembled and tending to draw the cover down upon the top C. The arms of the spring being diametrically opposite exert an equal pressure upon both sides of the cap, preventing any binding action, and, on account of their downward inclination, permitting the cover to be raised a distance equal to the distance between the bottom of groove N and the top of groove F, less the thickness of the spring, between which points the spring-arms would be clamped were the cover raised to its extreme height.

The cover may be readily forced into position by exerting a downward pressure thereon and at the same time turning it slightly in the direction in which the arms extend, thus forcing the arms back into groove F, allowing the cover to descend, the spring-arms entering groove N immediately it comes opposite them.

Assuming the cover to be closed, or in the position shown in Figs. 1, 3, and 5, wherein the stud E is within opening M, and it be desired to inject or pour oil into the oil-hole, the operator takes hold of cap L, raises it free from stud E, and turns it around in either direction until openings D and M are in line. Stud E meanwhile bears upon the under face of the cap and holds said cap in its elevated position, as indicated in Fig. 6. When it is desired to close the opening, the cap is turned until opening M comes into alignment with stud E, when the spring draws it down, effectually closing the cover to all dust and other extraneous matter.

The construction shown is simple and effective. It permits free use of both hands when the cap is once opened, and when closed remains so and is not opened by the jar or movement of the machinery to which it may be attached.

Having thus described my invention, what I claim is—

1. In an oil-hole cover or cap, the combination of a hollow stem or post provided with an opening in its upper end; a stud upon the upper end of the post; and a cap rotatably

mounted upon the upper end of the post and provided with an opening, said cap being capable of rotation so as to bring its opening into alignment with the stud or with the opening formed in the post.

2. In an oil-hole cover or cap, the combination of a hollow stem or post provided with an opening in its upper end, and an oppositely-disposed stud rising therefrom; a cap mounted on said post and provided with an opening to one side of its center, said cap being rotatable whereby its opening may be brought into alignment with the opening in the post or with the stud thereon; and means for drawing said cap down upon the post when the stud and opening in the cap are in alignment.

3. In an oil-hole cover or cap, the combination of a hollow stem or post provided with an opening at its upper end, and an upwardly-extending eccentric stud; a cap fitting over the upper end of the post also provided with an opening said opening being to one side of the center of the cap; and means for holding the cap upon said stem allowing longitudinal and rotary motion thereof relative to the post.

4. In an oil-hole cover or cap, the combination of a hollow post or stem provided with an opening at its upper end to one side of its center; a stud extending upwardly from said upper end at a point approximately opposite said opening; and a cap formed with an opening to one side of its center, rotatably mounted upon said post, said cap also being capable of endwise movement, the stud upon the post being designed to enter the opening in the cap when said opening and the opening in the post are out of alignment.

5. In an oil-hole cover or cap, the combination of a hollow stem or post provided with an upwardly-extending stud, and with an opening in its upper end; there being a groove F formed around the post below the opening; a spring II; and a cap designed to be fitted over the upper end of the post, said cap having formed therein an annular groove or channel N designed when the parts are assembled

to receive the ends of the spring and to permit a rotary and endwise movement of the cap, substantially as shown and described. 50

6. In an oil-hole cover or cap, the combination of a hollow stem or post provided with an opening at its upper end and with an upwardly-extending stud; a channel F formed around said post below the opening; diametrically opposite openings G; a spring II mounted in said openings the free ends of which extend downwardly and around said post; and a cap designed to fit over the upper end of the post, said cap having an internal 60 annular groove N formed therein designed to receive the ends of the spring whereby a longitudinal and rotary motion may be given to the cap.

7. In an oil-hole cover or cap, the combination of a hollow stem or post provided with an opening at its upper end to one side of the center thereof and an upwardly-extending stud E; a groove or channel F formed around the post at a point immediately below the top; 70 a spring II the free ends of which extend downwardly and around the post; and a cap designed to fit over the upper end of the post, said cap being provided with an opening M and an internal channel or groove N to receive the free ends of the spring, substantially as and for the purpose set forth. 75

8. In an oil-hole cover or cap, the combination of a hollow stem or post provided with an opening at its upper end and with an upwardly-extending stud; oppositely-disposed spring-arms extending around said post below the opening; a cap designed to fit over the upper end of the post, said cap being provided with an internal annular groove designed to 80 receive the spring-arms, substantially as and for the purpose set forth; and an opening formed in the upper face of the cap.

In witness whereof I hereunto set my hand in the presence of two witnesses.

FRANK D. WINKLEY.
